CLAIM

I claim the ornamental design for a combination pepper spray dispenser and glass breaking implement, as shown and described.

DESCRIPTION

FIG. 1 is an exploded bottom perspective view of a combination pepper spray dispenser and glass breaking implement, showing my new design;

FIG. 2 is an exploded top perspective view thereof;

FIG. 3 is an exploded front elevational view thereof;

FIG. 4 is an exploded rear elevational view thereof;

FIG. 5 is an exploded right-side elevational view thereof;

FIG. 6 is an exploded left-side elevational view thereof;

FIG. 7 is an exploded top plan view thereof;

FIG. 8 is an exploded bottom plan view thereof; and,

FIG. 9 is a bottom perspective view thereof.

The broken lines showing a key ring, spray canister, and finger grips in the figures depict environmental matter and form no part of the claimed design.
